DESIGN FOR A COMBINED SACHET BAG
AND PERFUME BOTTLE CONTAINER

Elizabeth N. Graham, New York, N. Y.

Application February 20, 1947, Serial No. 137,034

Term of patent 14 years

(Cl. D86—10)

To all whom it may concern:

Be it known that I, Elizabeth N. Graham, a citizen of the United States of America, residing in New York city, county of New York, and State of New York, have invented a new, original, and ornamental Design for a Combined Sachet Bag and Perfume Bottle Container, of which the following is a specification, reference being had to the accompanying drawing, forming part thereof, wherein,

bottle container shown in Figures 1, 2 and 3.

I claim:

The ornamental design for a combined sachet bag and perfume bottle container, substantially as shown.

ELIZABETH N. GRAHAM.
